RAIN ACTUATED WINDOW CLOSER

Alfred Mumenthaler, Washington, D. C., assignor
to Jane W. Bangs, Washington, D. C.

Application December 15, 1947, Serial No. 791,713

3 Claims. (Cl. 268—123)

1

The present invention relates to a device for closing windows. More particularly the invention pertains to a mechanism responsive to deposit thereon of rain drops, an element which will tear or rupture when moistened, automatically releasing latching means to permit actuation of a spring-operated mechanism designed to move a window sash or the like to a closed position.

It is frequently necessary for occupants of houses and apartments to be absent therefrom for several hours and it is customary during the summer months to close the windows in living quarters to prevent water from entering the windows should there be a sudden storm. Rooms are, therefore, inadequately ventilated and temperatures therein are abnormally high. This invention is intended to obviate these conditions and permit the occupant, while absent, to leave windows open.

It is an object of the invention to provide mechanism which, when positioned in adjacent relation to a window, will automatically close the window should rain come in contact with the mechanism.

It is another object of the invention to provide means for regulating the tension or pull on the window closing mechanism to permit adjustment thereof in accordance with the force required to close the window.

It is a further object of the invention to provide inexpensive and replaceable means responsive to moisture as an element of the releasing mechanism.

Other objects will be apparent from the following description of the invention when taken with the drawings illustrating a preferred form thereof and in which

Fig. 1 is a perspective view of one embodiment of the invention;

Fig. 2 is a rear elevation of the device shown in Fig. 1;

Fig. 3 is a side elevation of the mechanism;

Fig. 4 is a section taken on line 4—4 of Fig. 2;

Fig. 5 is a top view, partly in section, of the device;

Fig. 6 is a section taken on line 6—6 of Fig. 5;

Fig. 7 is a fragmentary section, similar to Fig. 6, with the latch release in another position;

Fig. 8 is a section taken on line 8—8 of Fig. 5; and

Fig. 9 is a section taken on line 9—9 of Fig. 5.

In the drawings there is shown a spring housing 10 having a removable cover plate 11 secured in place by means to be described hereinafter.

2

One end of a spiral spring 12 is fastened to the housing by means of a rivet 13, the other or inner end of the spring being secured to shaft 14 journaled in the side of the housing. This shaft extends through the housing and has keyed or otherwise fastened thereto a disc 15 having therein a recess 16 accommodating a slidably pawl 17 urged radially outward by spring 18. Rotatably mounted on shaft 14 is a spool consisting of an annular ring 19 and separate circular flanges 21, 21' held to the ring and to each other by screws 22. It will be observed from Fig. 4 that ring 19 is provided with ratchet recesses 23, one of which pawl 17 enters, a one-way clutch thus forming a connection between the ring and disc 15. Ring 19 is also provided with a recess 24 through which a screw-threaded pin 25 passes, the pin forming an anchor for flexible cord 26 adapted to be wound around the spool. The free end of the cord has attached thereto a ring 27 or the like for connection to a part of a movable window sash. In Figs. 6 and 8 it will be seen that there is formed integral with shaft 14 an annular flange 28 having a plurality of ratchet-like notches 29 in its periphery.

Attached to what will be designated as the top of the spring housing by means of screws 30 is a bracket 31 comprising an inverted channel-like frame forming a support for latching mechanism 32. Secured to or formed integral with the bracket are upstanding ears 33 forming bearings for a shaft 34 on which are pivotally mounted latch member 35 and release arm 36, each independently pivoted. It is to be noted, however, that arm 36 is provided with an extension 37 adapted, when moving clockwise as seen in Fig. 7, to engage finger 38 on the latch member to rock the latter. Normally the release arm and latch member occupy the position shown in Fig. 7, arm 36 being urged to this position by spring 39 surrounding rod 41 and bearing against flange 42 on the bracket and nut 43 on the rod. The rod is pivotally fastened to arm 36 at 44. There is also secured to arm 36 a finger piece 45 having an offset portion 46 adapted to be engaged by a ribbon 47 of material such as paper which, when moistened, readily ruptures or breaks. The paper ribbon is folded over the finger offset and, after the finger has been lowered and spring 39 thereby compressed, the free ends of the ribbon are clamped between bracket 31 and a movable clamping plate 48, the latter being urged into clamping position by nut 49 on the threaded post 51 which passes through the clamping plate. The clamping plate is provided with a collar through

which post 51 also passes, this collar bearing against spring 52 surrounding the post and abutting the opposite side of the bracket so that when the nut is loosened the clamping plate is urged away from the bracket.

The housing is supported by a bracket 53 secured thereto by screws 54. These screws together with screws 38 hold the housing between the flanges of the lower and upper brackets and thus retain the cover plate 11, those screws on the cover side of the housing threading into tapped holes in the cover plate so that the latter is constrained against either lateral or rotary movement when the parts of the device are assembled.

In operation the cord 26 is wound around the spool and the latter rotated thereby until spiral spring 12 is wound with sufficient tightness readily to exert the necessary pull on the window sash to which it is attached by means of ring 27 to close the window. Because of the one-way clutch connection between the spool and the spring, the window may be moved manually toward its closed position without disturbing the latching mechanism to permit further winding of the spring, thus permitting adjustment of the closing mechanism to insure sufficient storage of power in the spring to close the window when the latch is released. As indicated in the drawings, there are two recesses 23 to permit oscillation of the spool through arcs of less than 360° with subsequent reengagement of the clutch parts. It should be noted that, when finger 45 is held down by the paper ribbon, the latch member 35 may be manipulated to engage or disengage the notches 29 while adjustments are being made.

It is obvious from the foregoing description of the mechanism and its operation that there is provided by the present invention an automatic rain responsive closure operator capable of adjustment to meet the variations in force necessary to close windows of different types and weights. Even where windows may be of the same size and weight, because of irregularities or ill-fittings the friction to be overcome may vary over a wide scale. The present mechanism is designed to overcome these difficulties.

It is also apparent that the cord can be wound around the spool only in the proper direction to tighten the spring because if it is wound in the reverse direction the cord cannot be pulled, the one-way clutch thus preventing reverse winding.

While the embodiment illustrated and described is intended to lower vertically sliding sashes, it is obvious that it is readily adapted to close other types of windows whether they be sliding or swinging sashes. While paper ribbons are preferred, there are other materials which react similarly under the stated conditions and it is, therefore, intended that their use be contemplated in practicing the invention.

Having described my invention what I claim as new and desire to secure by Letters Patent is:

1. Mechanism for closing a window comprising a rotatable shaft, a spring secured at one end

- to said shaft, means for fixedly anchoring the other end of said spring, a spool, a one-way clutch connecting said spool and said shaft, a flexible element secured at one end to the window and at its other end to said spool, said element being adapted to be wound on said spool and to rotate said shaft to store power in said spring, latching means for constraining said shaft against rotation, means rupturable when moistened for holding said latching means in latching relation to said shaft, and means operable when said holding means is ruptured for releasing said latching means to permit said spring to close the window.
15. 2. Mechanism for closing a window comprising a rotatable shaft, a spring secured at one end to said shaft, means for fixedly anchoring the other end of said spring, a spool, a one-way clutch connecting said spool and said shaft, a flexible element secured at one end to the window and at its other end to said spool, said element being adapted to be wound on said spool and to rotate said shaft to store power in said spring, an annular flange on said shaft, said flange having a plurality of notches in its periphery, latching means selectively engageable in any one of said notches to constrain said shaft against rotation, means rupturable when moistened for holding said latching means in engagement with said one notch, and means operable when said holding means is ruptured for releasing said latching means from said one notch to permit said spring to close the window.
3. A latching mechanism for a window closer of the class described, comprising a shaft, a pair of rockable arms independently pivoted on said shaft, means on one of said arms for engaging the other of said arms when said one arm is rotated in one direction only, spring means for rocking said one arm in said one direction, said other arm being engageable with a rotatable member to prevent rotation thereof and being disengaged from the rotatable member when said one arm engages said other arm, said one arm urging said other arm out of engagement with said rotatable member when the one arm engages the other, means for holding said one arm out of engagement with said other arm, said holding means being rupturable when moistened, and means on said other arm for manually disengaging said other arm from said rotatable member independently of said one arm.

ALFRED MUMENTHALER.
